(57) **CLAIM**

The ornamental design for a tyre, as shown and described.

DESCRIPTION

FIG. 1 is a front, left side perspective view of a tyre showing our new design;

FIG. 2 is a front elevation view thereof;

FIG. 3 is a left side view thereof, the right side view being the mirror image thereof;

FIG. 4 is a partial front elevational view taken from FIG. 2 and shown in an enlarged scale;

FIG. 5 is another front elevational view taken from FIG. 2, depicting the central circumferential section of the tread pattern;

FIG. 6 is an enlarged fragmentary front view showing a channel between laterally adjacent left cleats of the tyre of our new design;

FIG. 7 is an enlarged fragmentary front view similar to FIG. 6 showing one of the right cleats medial and adjacent to the central circumferential section of the tread pattern as depicted in FIG. 5; and,

FIG. 8 is an enlarged fragmentary front view similar to FIG. 7 showing two circumferentially adjacent right side cleats, a cleat medially inboard and adjacent thereto, and a channel therebetween.
